Primary Examiner—Celia A. Murphy(74) *Attorney, Agent, or Firm*—St. Onge Steward Johnston & Reens LLC(57) **CLAIM**

I claim the ornamental design for an outsole for a shoe, as shown and described.

DESCRIPTION

FIG. 1 is a bottom view of an outsole for a shoe showing my new design;

FIG. 2 is a right side view thereof;

FIG. 3 is a left side view thereof;

FIG. 4 is a front view thereof; and

FIG. 5 is a rear view thereof; and,

FIG. 6 is a bottom perspective view thereof.

The broken line showing a shoe upper in FIGS. 2-6 illustrates the portion of the design that forms no part of the claim. The broken circular outline in FIGS. 1 and 6 represents the boundary of the design with the line itself and the area within forming no part of the claim.
